UMBRELLA

James C. Witty, Troy, Ohio, assignor to The Troy Sunshade Company, Troy, Ohio, a corporation of Ohio

Application June 28, 1950, Serial No. 170,819

1 Claim. (Cl. 135—20)

1

This invention relates to umbrellas, and more particularly to umbrellas of comparatively large size such as beach or garden umbrellas or the like.

Considerable difficulty is sometimes encountered in raising and collapsing large umbrellas owing to the substantial amount of force required to produce the tension in the ribs for holding the canopy properly in use. It is frequently impossible, particularly for a woman or child, to raise or lower the canopy of such an umbrella while the standard is erect, since only by inverting the standard and pressing against the ground or some other abutment can sufficient force be developed to overcome the rib tension. It is also difficult to collapse the umbrella top, and this operation is attended by considerable possibility of pinching the fingers or otherwise suffering discomfort. Also another difficulty in raising and lowering a conventional beach or garden umbrella is that the large radius of the canopy requires the force on the part of the user to be exerted at a very awkward angle and frequently when off balance.

The present invention overcomes these well known difficulties and inconveniences of the conventional beach umbrella structure by providing an umbrella which can be conveniently erected when the standard is upright and in which the main force required for erection is exerted downwardly along the standard. This simple and easy operation is obtained by providing an axially movable extension on the upper end of the standard and securing the top crown to this extension instead of to the standard. With this construction, when the canopy is to be erected and the runner is moved to its raised position in the usual way, the extension and top crown move with respect to the standard to an upper position in which the canopy is fully extended but the ribs are under substantially no tension. Erection of the top is then completed by pulling down on the extension, as by means of a suitable cord or chain, to develop the proper tension in the ribs, and the extension is then retained in this lower position for use of the umbrella.

It will be seen that with this construction and operation, the standard can readily be set in the ground in upright position after the runner has been raised, which requires comparatively little force, but while the extension is still in its upper position and the ribs are not under tension. Movement of the extension to its lower position can then be effected by pulling directly downwardly from a convenient position below the canopy and adjacent the standard, which is con-

2

siderably more comfortable for the user and also may be done without the dangers of pinched fingers or the like commonly encountered with the usual construction. Collapsing of the umbrella is equally simple and convenient, it being necessary merely first to release the extension for movement to its upper position under the releasing tension in the ribs, after which the runner is released and retracted in the usual way.

It is one of the principal objects of the present invention to provide an umbrella construction particularly useful in connection with beach, garden or other umbrellas of relatively large size wherein the movement of the runner to its raised position is effected substantially without developing tension in the ribs, the raising of the canopy is completed by pulling downwardly on a movable portion of the frame, and the collapse of the umbrella is similarly accomplished by first pulling downwardly on a movable member.

Another object of the invention is to provide such an umbrella construction which does not materially differ in appearance from conventional beach and the like umbrellas but which requires considerably less effort for erection and collapse and in which the force required for raising and lowering the canopy is exerted in a more comfortable position for the user than with conventional umbrellas.

It is also an object of the invention to provide an umbrella construction of the above type in which the canopy is simple and easy to raise or collapse while the standard is in an upright position and in which the force required for raising and collapsing the top is exerted in such direction as to maintain the standard upright.

Other objects and advantages of the invention will be apparent from the following description, the accompanying drawing and the appended claim.

In the drawing—

Fig. 1 is a view in side elevation, partly broken away, illustrating an umbrella construction in accordance with the invention and shown in erected position;

Fig. 2 is a fragmentary view on an enlarged scale showing the structure and operation of the umbrella frame;

Fig. 3 is a fragmentary view at right angles to Fig. 2; and

Fig. 4 is a view similar to Fig. 3 showing the relation of the parts in the collapsed position of the umbrella top.

In the drawing, which illustrates a preferred embodiment of the invention, the standard is

3

is shown as a hollow tube pointed at 11 for insertion in the ground and carrying a canopy 12 having the usual ribs 13 and braces 14 of steel or other suitable material. The runner 15 is 5 slideable on the standard 10, and a spring catch or stop spring 16 is provided on the standard for releasably retaining the runner in its raised position for expansion of the canopy.

An extension 20, shown as a sleeve, is telescoped within the upper end of the standard 10, and the top crown 22 is secured to the upper end of this extension instead of to the standard, and thus connects the ends of the ribs to the extension 20. The extension 20 is provided with an elongated axial slot 24 which receives a stop pin or screw 25 in the standard, and this slot and pin cooperate to establish upper and lower limit positions for the extension 20 with respect to the standard. A chain 26 is secured by a bolt 27 to the standard. A chain 26 is secured by a bolt 27 to the upper end of the extension 20 and hangs 20 downwardly therefrom. A handle 30 provided with a hook 31 is secured to the lower end of this chain, and a hole 33 for receiving the hook is provided in a side of the standard.

When it is desired to erect this umbrella, the runner 15 is first moved to its raised position above the stop spring 16. With the hook 31 disengaged from the standard, the extension 20 will be free to move to its upper limit position shown in full lines in Fig. 2, and in this relative position of the parts, the canopy 12 will be substantially fully expanded but the ribs 13 will be under no appreciable tension. Thus this movement of the runner is accomplished with comparatively little force. Thereafter, the handle 30 is grasped, 35 and pulled downwardly to move the extension 20 similarly downwardly through chain 26 and thus to develop the desired tension in the ribs 13. Fig. 2 shows in dotted lines the positions of the extension 20 and ribs 13 in the lower limit position of the extension, and the parts are held in this position by engaging the hook 31 in the hole 33 as also shown in dotted lines in Fig. 2.

The standard 10 may be set in the ground at any desired stage in the erection of the umbrella, but it will usually be found most convenient to do so either before or after the runner 15 has been raised but before completing erection of the top. Then the final step of moving the extension to its lower position is effected by pulling directly downwardly on the handle 30 and chain 26, and it is thus not necessary to exert any counterforce or otherwise hold the standard since this downward pull will have no effect on the standard other than to set it more firmly in the ground. Collapsing of the umbrella top can similarly be 55 effected simply and easily while the standard is upright, it being necessary merely to pull down sufficiently on the handle 30 to release the hook

31 and permit the extension 20 to move to its released upper position under the releasing tension in the ribs. In fact, with the hook 31 formed as shown of generally S-shape, it is merely necessary to pivot the handle 30 about the outer loop of the S against the standard to effect withdrawal of the hook from the hole 33.

It will accordingly be seen that this umbrella construction has outstanding advantages of simplicity and ease in use. Erection and collapsing of the umbrella top are easily effected with comparatively little effort while the standard is upright, and at the same time the effort which is required is so directed as to avoid uncomfortable or awkward movements or position on the part of the user. Also, this umbrella construction is considerably easier to handle in the wind such as is often encountered on a beach, since if desired the standard can be firmly set in the ground before the top is raised at all, and the same is true of the operation of lowering the top.

While the form of apparatus herein described constitutes a preferred embodiment of the invention, it is to be understood that the invention is not limited to this precise form of apparatus, and that changes may be made therein without departing from the scope of the invention which is defined in the appended claim.

What is claimed is:

An umbrella structure for beach and garden umbrellas and the like, to facilitate raising and collapsing of the top thereof while the umbrella is erect, comprising a hollow standard, an extension mounted for telescoping movement within the upper end of said standard, cooperating pin and slot means on said standard and said extension for guiding and limiting the relative telescoping movement thereof; a top including a canopy and ribs carried by the upper end of said extension, braces attached to said ribs, a runner connected with said braces and slideable upwardly on said standard below said extension to effect expansion of said top and movement of said top and extension to the uppermost position thereof for minimizing the development of tension in said ribs; means depending from said extension for pulling the same downwardly to develop tension in said ribs, and means for releasably securing said depending means to said standard to retain said top with said ribs under tension.
